COMBINED MOLDED SEAT AND BACK

Chester J. Barecki and Bror W. Henrikson, Grand Rapids, Mich., assignors to American Seating Company, Grand Rapids, Mich., a corporation of New Jersey

Application March 25, 1957, Serial No. 45,406

Term of patent 14 years

(Cl. D15—8)

We claim:

The ornamental design for a combined molded seat and back, substantially as shown.
